UNITED STATES PATENT OFFICE.

FRANK E. WOLCOTT, OF INDIANAPOLIS, INDIANA.

POCKET-FUMIGATOR.

SPECIFICATION forming part of Letters Patent No. 772,993, dated October 25, 1904.

Application filed December 2, 1903. Serial No. 183,487. (No model.)

To all whom it may concern:

Be it known that I, FRANK E. WOLCOTT, a citizen of the United States, residing at Indianapolis, in the county of Marion and State of Indiana, have invented certain new and useful Improvements in Pocket-Fumigators, of which the following is a specification.

The object of my invention is to provide a convenient means for warding off contagious diseases. Where epidemics of such diseases (such as smallpox) prevail, it is a matter of great importance that persons whose occupation is such as to require them to pass about freely should have some means of preventing or reducing the danger of taking such disease. It is also necessary that such means should be such as to be conveniently carried about and easily used and also such that the remedial agent may be easily, quickly, and inexpensively renewed.

My invention therefore consists of a vessel containing an absorbent material suitable to receive and diffuse the remedial agent with a screen-cover secured therein over the absorbent material through which the remedial agent may be diffused and provided with a tightly-closing cover which when applied will prevent the remedial agent from becoming dissipated when its services are not required, as will be hereinafter more particularly described and claimed.

Referring to the accompanying drawings, which are made a part hereof, and on which similar reference characters indicate similar parts, Figure 1 is a perspective view of a vessel and its contents embodying my said invention; Fig. 2, a perspective view of the cover thereto; and Fig. 3, a central vertical sectional view through the whole on a considerably-enlarged scale.

This vessel consists of a body 21, preferably formed from sheet metal, having an outer ledge 22, against which the edge of the cover will bear when said cover is applied, and an inner 45 rim or ledge 23, beneath which the perforated retaining member 25 may be placed and thus

held in position, and a suitable absorbent material 24, placed within the vessel and under said perforated plate, said retaining member or plate 25 being preferably formed of wire-cloth, and a cover 26, adapted to be placed on the box and form a tight inclosure when desired.

The box or vessel being filled with an absorbent material 24 and being saturated or charged with a suitable remedial agent, the retaining member or screen-plate 25 is put in place, and said absorbent material is thus securely held within the inclosure. The remedial agent may be applied to the absorbent material either before or after the same is inserted in the box and may be replenished whenever desired.

These fumigators are made small enough to be carried in a pocket and should be so carried by the individual needing the use of it and can be taken out and the cover removed, so that the benefit of the remedy may be obtained whenever desired. When not in use, the cover is fitted so closely as to prevent the dissipation and waste of such agent.

Having thus fully described my said invention, what I claim as new, and desire to secure by Letters Patent, is—

A pocket-fumigator consisting of a box, the main body of which is formed of a single piece having at its upper open end an annular portion terminating in an annular lip 23 which is turned inward and downward, a reticulated member 25 passed through the open end of said main body and held in place by said lip, and a removable cover 26 fitting closely upon the annular upper open end of the main body, substantially as and for the purpose set forth.

In witness whereof I have hereunto set my hand and seal, at Indianapolis, Indiana, this 30th day of November, A. D. 1903.

FRANK E. WOLCOTT.
